UNITED STATES PATENT OFFICE.

JESSE LEWIS, OF SIBLEY, IOWA, ASSIGNOR OF THREE-FOURTHS TO WALTER BANCROFT STEVENS, OF SIBLEY, IOWA, AND CHARLES S. McLAURY, OF SHELDON, IOWA.

LOCKING SINGLETREE-HOOK.

SPECIFICATION forming part of Letters Patent No. 687,160, dated November 19, 1901.

Application filed April 19, 1901. Serial No. 56,586. (No model.)

To all whom it may concern:

Be it known that I, JESSE LEWIS, a citizen of the United States, residing at Sibley, in the county of Osceola, State of Iowa, have invented certain new and useful Improvements 5 in Locking Singletree-Hooks, of which the following is a specification.

The object of this invention is to provide a locking singletree-hook of simple, strong, 10 durable, and inexpensive construction which may be applied to the end of a harness-trace in lieu of the usual cockeye and be readily and quickly attached or detached from the singletree, and when in use will throw the 15 strain of the pull entirely upon the end of the singletree, and the device will stand in a position when in use so that it may not readily become caught in the harness or other parts and cannot be easily broken or 20 displaced; and my object is, further, to provide a device of this class which when locked cannot become detached by any strains or pulls to which such hooks are ordinarily subjected—as, for instance, in going down a hill with the 25 traces slack, swaying from side to side.

My invention consists in certain details in the construction, arrangement, and combination of the device whereby the objects contemplated are attained, as hereinafter more 30 fully set forth, pointed out in my claim, and illustrated in the accompanying drawings, in which—

Figure 1 shows a top or plan view of the end of the singletree with my device attached thereto and also the end of a trace with the other part of the device connected therewith and in position adjacent to the part of the singletree. Fig. 2 shows an end elevation, with parts broken away, of the device in its 35 locked position.

Referring to the accompanying drawings, I have used the reference-numeral 25 to indicate a socket attached to the end of the singletree and having a rearward flat extension 26 thereon, provided with a vertical slot 27 in its rear end. Mounted in the central portion of this rearward extension is a turning-block 28, made of one piece of metal and forged into said central portion, said turning-block 40 28 having a slot 29 therein designed to coin-

55 coincide with the slot 27. Said lock is provided with flanged edges to mate with like surfaces on the extension 26, so that the said lock may freely turn in the extension and be incapable of up-and-down movement.

The numeral 30 is used to indicate a metal loop of a size designed to admit the end of the singletree. At its rear end is a straight flat surface 31 of a size and shape designed to enter the slots 27 and 29 and to be wholly contained within the slot 29. At the forward end of the loop 30 is a detachable screw 32, which is designed to pass through the end of the trace in lieu of the usual screw in a cock-eye. To prevent oscillation of the loop 30, I 65 provide a notch 33 opposite the straight flat surface 31.

In practical use the loop is connected with the trace, as set forth, and the socket is attached to the singletree, as shown, and extended rearwardly, and when it is desired to attach the trace on the singletree the rear end of the trace is bent, as shown in Fig. 2, and the straight edge 31 passed through the slot 27 into the slot 29. Then the loop 30 is 70 turned to overlap the end of the singletree and the trace is extended straight forwardly. When in this position, it is obvious that all the pulls upon the trace will be transmitted direct to the rear edge of the singletree, and, 75 further, that the said loop cannot become detached until the trace is slackened and the loop moved to a position extended straight rearwardly. It is obvious that this position cannot be assumed by the loop in any 80 of the usual uses to which the trace is subjected, but must be moved rearwardly by hand in order to be detached. Furthermore, the device is of simple, strong, and durable 85 construction and there are no parts which can 90 become entangled with the harness.

I claim as my invention—

In a locking singletree-hook, a socket, a projection on the rear end thereof having a rounded opening therein and a slot opening 95 rearwardly from said opening, the upper and lower edges of said opening beveled, a turning-block made of one piece of metal and notched radially mounted for rotation in said rounded opening, said turning-block having 100

a grooved periphery adapted to fit snugly the walls of said rounded opening, in combination with a loop attached to a trace and arranged to enter said slot in the projection and seat in the notch of and turn with the block, the inner edge of said loop formed with a notch on the median line thereof to receive the said projection at the innermost edge of

10 said rounded opening therein to limit and determine oscillation of said loop on the periphery of said socket.

JESSE LEWIS.
